PORTABLE BIDET

Georgia Di Pasquale, 205 Birchwood Road,
New Milford, N.J. 07646

Filed Apr. 24, 1968, Ser. No. 11,596

Term of patent 14 years

U.S. Cl. D23—51
Int. Cl. D23—02

FIG. 1

FIG. 2

FIG. 3

FIG. 4

FIG. 5

FIG. 1 is a top plan view of a portable bidet embodying my new design.

FIG. 2 is a bottom plan view of the same.

FIG. 3 is a side elevational view of the same.

FIG. 4 is a rear elevational view of the same.

FIG. 5 is a front elevational view of the same.

The water connector and its securing straps have been broken away in FIGS. 1 and 2 to indicate indeterminate length, while said elements have been omitted from FIGS. 3, 4 and 5 for convenience of illustration.

I claim:

The ornamental design for a portable bidet, substantially as shown and described.
